E. D. JOHNSON

SIGNALING CIRCUITS

Filed Feb. 7, 1918

Inventor:
Edgar D. Johnson.

J. A. Roberts Atty.

UNITED STATES PATENT OFFICE.

EDGAR D. JOHNSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING CIRCUITS.

Application filed February 7, 1918. Serial No. 215,930.

To all whom it may concern:

Be it known that I, EDGAR D. JOHNSON, a citizen of the United States, residing at East Orange, in the county of Essex, State 5 of New Jersey, have invented certain new and useful Improvements in Signaling Circuits, of which the following is a full, clear, concise, and exact description.

This invention relates to electric circuits 10 wherein a repeater or the like is connected between two transmission lines in one manner for transmission in one direction and in another manner for transmission in the opposite direction.

15 In my application Serial No. 213,523, Signaling systems and methods of operating the same, filed January 24, 1918, it is shown how means for reversing the connections of the repeater to the lines may be continually 20 operated, the reversal of the repeater connections being arrested in response to current impressed on the line to maintain the repeater connected in the proper manner, and to permit the transmission of current 25 in the proper direction through the repeater.

An object of the present invention is to 30 overcome a brief time-lag that exists in the above system by reason of the fact that the impression of current on the line serves to arrest the motion of all of the control relays associated with the reversing switch, and all of which are subsequently set in motion.

According to the present invention the 35 reversing switch operates in response to the continual actuation of some device, such as an interrupter, which is always in motion, the interrupter being removed from the control of the reversing switch by means of the 40 voice relay or other relay responsive to the incoming current. When the voice relay ceases to operate the continually operating interrupter immediately assumes control of the reversing switch, operating in the manner desired.

Another object of the invention is to 45 make more positive the control of the circuits by the voice-operated relay and to this end there is associated with the voice-operated relay an auxiliary relay which 50 opens the circuit while the voice relay is operating. The voice relay is provided with vibrating contacts, which serve to increase the resistance in the circuit in which they

are included. This resistance is more effectively increased, however, according to the present invention, by the use of the auxiliary relay, which positively keeps the circuit open while the voice relay is operating. 55

Further objects of the invention will be 60 made apparent in the following detailed description taken in connection with the accompanying drawing, in which the single figure shows diagrammatically a two-way repeater circuit embodying the invention. 65

In the drawing the repeater 1, which is here shown as of the mechanical type, although any other type may be employed, is adapted to be reversibly connected between the lines 2 and 3 by means of the relays or reversing switches 4 and 5. As shown in the drawings, the line 2 is connected through armature 6 and repeating coil 7 to the input side of the repeater, the output side of which is connected through repeating coil 8 and armature 9 to the line 3. It is obvious that with the armatures 6 and 9 in their alternate positions, the connection of the repeater 1 between the lines 2 and 3 is reversed, the line 3 being connected by way of the armature 9 and repeating coil 7 to the input side of the repeater, the output side of which, through the repeating coil 8 and armature 6, leads to the line 2. 70 75 80

The reversing switches 4 and 5 are operated by the relay 10, the armature of which, in the position shown, sends current from ground, through battery 11, to the solenoids 12 and 13 to ground, which attracts the armatures 6 and 9 to the position shown. When the armature 14 of the relay 10 assumes its alternate position, the battery 11 is connected in circuit with the solenoids 15 and 16, thereby moving the armatures 6 and 9 to their alternate positions and reversing the connection of repeater 1 to the lines. The operation of the relay 10 is controlled by means of the interrupter 17, the energizing circuit of which includes armature 18 and battery 19. With armature 20 85 90 95

of interrupter 17 in the position shown, the solenoid 21 of relay 10 is energized through a circuit which includes battery 11, solenoid 21, armature 20, armature 22 of a relay 23, and the vibratable contact 24 of an alternating current or voice-operated relay 25, which is permanently connected in shunt to the input side of the repeater as shown. The 100 105

movement of armature 20 of the interrupter to its alternate contact serves to substitute the solenoid 26 for the solenoid 21 in circuit with the battery 11, thereby moving armature 14 to its alternate position and reversing the switches 4 and 5. The interrupter 17 is continually operating and with armatures 22 and 24 closed, as they are when no current is impressed on the lines 2 and 3, the relay 10 and the reversing switches 4 and 5 oscillate their armatures in step with the movement of armature 20 of the interrupter. The continual operation of the switches 4 and 5 serves to point the repeater first in one direction and then in the other between the lines 2 and 3.

If voice current is impressed on the line 2 with the armatures of the relays in the position shown, the armature 24 of relay 25 is set into vibration, thereby sufficiently increasing the resistance in circuit with battery 27 to deenergize relay 23 and release armature 22. This serves to deenergize relay 10, thereby leaving armature 14 in the position shown irrespective of the continual operation of the armature 20 of the interrupter. As soon as relay 25 is deenergized due to the fact that currents are no longer impressed on line 2, armature 24 is released, thereby energizing relay 23, which attracts its armature and completes a circuit from ground through armature 24, armature 22, armature 20, to one or the other of the solenoids 21 or 26 and battery 11 to ground, thereby subjecting relay 10 again to the control of the interrupter 17, the relay 10 and switches 4 and 5 operating in step with the interrupter as before.

If voice current is impressed on line 2 at a time when the input side of the repeater is connected with the line 3, the voice relay 25 will not be operated until a later instant when the input side of the repeater is connected to the line 2, due to the fact that the relay 25 is permanently connected to the input side of the repeater.

If current, such as voice current, is impressed on the line 3 with the armatures in the position shown, the voice relay 25 will not be operated, as it is not in circuit with line 5 due to the position of the armature 9. Relay 25 will, however, be operated when the input side of the repeater is connected to the line 3 and the reversal will then be arrested, permitting the transmission of currents from line 3 through the repeater to line 2.

The invention is not limited to any particular type of interrupter or of control relay, and the circuit as a whole is adapted to amplify any kind of impressed currents, such as voice currents or ringing currents. Although the invention has been set forth with especial reference to its application to the repeating of voice frequency currents, it

is of course also applicable to the repeating of currents of other frequencies, whether higher or lower. It is understood that the invention is not limited to the particular circuit arrangement set forth herein, but is capable of embodiment in many and widely varied arrangements within the scope of the appended claims.

Certain broad aspects of this invention which are not claimed herein are claimed in my application Serial No. 406,731, Signaling systems, renewal of No. 212,461, filed January 18, 1918; Serial No. 212,462, Signaling systems, filed January 18, 1918; Serial No. 213,522, Signaling systems, filed January 24, 1918; and Serial No. 213,523, Signaling systems and methods of operating the same, filed January 24, 1918.

What is claimed is:

1. A repeater system comprising two lines, a repeater therefor, means for reversing the connections of said repeater to said lines, means controlling said reversing means, said controlling means operating continually during repeating, and means responsive to current impressed on said lines for preventing said continually operating means from operating said reversing means.

2. A repeater system comprising two lines, a repeater therefor, means for reversing the connections of said repeater to said lines, means comprising a movable contact for operating said reversing means, said contact assuming a plurality of positions for reversing said repeater, means for moving said contact while repeating, and means for assuming control of said reversing means independently of said contact.

3. In a system, a line, a repeater, means comprising a switch for reversibly connecting said repeater in said line for repeating alternately in opposite directions, and alternative means for operating said switch, one of said means continually opening and closing said switch, during repeating, independently of current impressed on said line.

4. In a system, a relay having an oscillatable armature, an interrupter having a vibrating armature controlling said relay for continually oscillating said relay armature, and a circuit unaffected by vibration of said interrupter armature, for operating said interrupter armature.

5. A repeating system comprising a line for supplying voice currents, a repeater therefor, means for connecting said repeater to and disconnecting said repeater from said line, a movable contact controlling said connecting and disconnecting means, means moving said contact continually while current is impressed on said line, and means responsive to current impressed on said line for assuming control of said connecting and disconnecting means.

6. The combination of a plurality of sta-

tionary contacts, a movable contact adapted to be cyclically connected therewith, a signal line connected to said movable contact, a contact adapted to operate at times in synchronism with said movable contact, motive means for maintaining said last-mentioned contact in motion while current is

impressed on said line, and connections for arresting the motion of said first-mentioned contact in response to current on said line. ¹⁰

In witness whereof, I hereunto subscribe my name this 18th day of January A. D., 1918.

EDGAR D. JOHNSON.
